UNITED STATES PATENT OFFICE

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY

HEEL DRILLING MACHINE

Application filed January 9, 1929. Serial No. 331,375.

This invention relates to drilling machines and is illustrated as applied to a drilling machine of the type employed to drill through the heel seat of a shoe into a heel which has been applied to the shoe.

5 A machine of the type referred to is described and claimed in my copending application Serial No. 54,046, filed Sept. 2, 1925, Patent 1,722,992, issued August 6, 1929, and 10 the present invention is herein illustrated as embodied in an attachment for that machine.

Machines of this kind are provided with a drill which is adapted to be fed manually downward through a previously formed 15 guide hole in a last upon which the shoe is mounted and to drill through the heel seat of the shoe and into the heel a hole for the reception of a screw fastener which is later to be inserted and tightened for the purpose of 20 clamping and holding the last, shoe and heel tightly together. It is essential that the fastener receiving hole be drilled deeply enough into the heel to permit the fastener to be 25 screwed far enough into the heel to hold the latter securely and it is equally important that the hole shall not be deep enough to weaken the heel materially or to approach too 30 closely to any of the surfaces of the heel.

Inasmuch as the drill enters the work at 35 the bottom of a deep guide hole in the last and the place on the work where the hole is to be drilled is entirely concealed from view, it is impossible to determine by inspection 40 how the drilling of the hole is progressing, and the use of any depth gage dependent upon co-operation with the work makes it necessary for the operator to rely upon his sense of touch to determine when the hole is finished. It will, therefore, be realized that a problem 45 of substantial difficulty is presented.

This problem was satisfactorily solved by the invention disclosed and claimed in my copending application, Serial No. 245,966, filed January 11, 1928, Patent 1,748,059, issued February 25, 1930, as long as the work supporting table of the drilling machine was vertically stationary but, inasmuch as the depth to which the drill penetrated the work was determined by a stop supported on a vertically stationary part of the machine com-

55 plications developed when the work supporting table was made vertically adjustable in accordance with the invention disclosed and claimed in my copending application Serial No. 127,034, filed August 4, 1926, Patent 1,757,163, issued May 6, 1930. In that case a change in the vertical position of the work supporting table made necessary a corresponding change in the adjustment of the drill stop and a single series of indicia upon the adjusting device for the latter could not correctly 60 indicate the proper setting for the drilling of holes of uniform depths with different adjustments of the work supporting table.

65 It is an object of the present invention to provide in a heel drilling machine improved means for positively and definitely determining the point to which the hole shall be drilled in the work by engagement with the work supporting element of the machine, regardless of the vertical position of said work supporting element when the hole is being drilled.

70 With this object in view an important feature of the invention consists in the provision of an improved depth gage co-operating with the work support to prevent feeding movement of the drill past a predetermined point in the work and comprising a carrier, a gage member slidable in said carrier, means for securing the gage member in various definite positions of adjustment in the carrier, and additional means for resisting movement of the gage member through the carrier sufficiently to prevent said member 75 from dropping when the securing means is released. The securing means may advantageously comprise spaced teeth upon the gage member and a co-operating hook upon the carrier arranged to engage any one of 80 said teeth to secure the gage in any of said various definite positions. In the illustrated machine the gage carrier is secured in fixed longitudinal relation to the drill holder, as by a clamp, and, therefore, moves with the 85 holder and the drill.

Invention is also to be recognized in the illustrated embodiment of means for resisting movement of the gage member through the carrier, comprising a continuously ef- 100

fective, yielding friction device operating automatically upon the gage member with sufficient force to prevent its weight from causing it to move in its holder.

5 These and other features of the invention and the benefits gained by its use will be better understood and appreciated from the following detailed description of a good practical embodiment thereof, when read in connection with the accompanying drawings, in which

10 Fig. 1 is a view in front elevation of a structure embodying the invention, showing the action of the depth gage when the drill 15 has penetrated to the desired point in the work;

15 Fig. 2 is a similar view illustrating the means for facilitating the setting of the drill in its holder; and

20 Fig. 3 is a perspective view of the drill point engaging anvil.

25 Referring now to the drawings, 10 indicates the manually operable drill holder of a machine such for example as that disclosed in my application Serial No. 54,046 hereinbefore referred to. The holder 10 is provided with a rotating chuck 12 in which the drill 14 is secured by a set screw 16. By loosening the set screw 16 the drill may be ad- 30 justed vertically in the chuck to determine the depth to which the drill will penetrate the work, as will presently be more fully explained.

35 The surface of the tread plate of a work support upon which a lasted shoe 18 and a heel 20 are sustained is indicated at 22. This work support may either be stationary or vertically movable, since the depth to which the drill may penetrate is accurately prede- 40 termined entirely independently of the position of the work support, and the drill, which is rotated continuously, is inserted through a guide hole in the last 24 which is in the shoe and fed downward through the heel seat of the shoe into the heel, as shown in Fig. 1.

45 In order accurately to determine the depth to which the drill 14 shall penetrate the heel there is provided a gage carrier 26 having a clamping collar 28 by means of which it may be securely attached to the drill holder 10 by tightening a clamping screw 30.

50 The carrier 26 has formed in it a guide passage 32 which is parallel to the axis of the drill and in which is slidably fitted a gage member 34.

55 The upper portion of the gage member 34 is provided with a series of teeth 36, spaced one-eighth of an inch apart, and indicia 38 60 are provided on the face of the gage to denote which of the teeth 36 is to be used when operating upon a heel of a given height.

65 Pivoted at 40 in the gage carrier is a hook 42 against the tail portion of which bears a spring 44 which tends at all times to press

the hook into engagement with one of the teeth 36. The inner end of the spring 44 is surrounded by a cup 46 which presses against the flattened side 48 of the gage, or the tops of the teeth 36, with enough pressure to produce sufficient friction to prevent the gage from dropping out of its carrier when the hook 42 is released.

70 The lower end of the gage 34 is provided with a gaging surface 50 adapted to engage the surface 22 of the work support. A shoulder 52 is also provided upon the gage and is designed for use in the operation of setting the drill in its holder.

75 The means provided for facilitating the setting of the drill in its holder will now be described. Referring to Fig. 2 a fixture 54 is illustrated as secured immovably to a portion 56 of the frame of the machine by a set screw 58 although this detail is immaterial since the member 54 might equally well be an integral portion of the machine frame. A vertical socket 60, in which the portion of the gage 34 below the shoulder 52 fits snugly, is formed in the fixture member 54, which is 80 provided with a horizontal flat reference surface 62 adapted to be engaged by the shoulder 52 as shown.

85 In the member 54 there is also provided a vertical passage, parallel to the socket 60, in which is fitted a vertically adjustable anvil 64 having a flat upper surface 66 which, when the anvil is in operative position, is horizontal and parallel to the surface 62.

90 A manually operable pin 68, movable in 100 and out in the fixture element 54, is adapted to enter selectively any one of a plurality of holes 70 formed at different points in the height of the anvil 64, enabling the anvil to be secured in various adjusted positions in 105 which its upper face 66 is at correspondingly different levels. The holes 70, in addition to being at different heights, are distributed around the circumference of the anvil and in alignment with each hole there is provided 110 an indicium 72 denoting the depth of the hole which will be drilled in the work when the setting of the drill in the chuck 12 is effected while the pin 68 is in the hole 70 corresponding to said indicium. For example, 115 when the anvil is set with the mark 3-8 facing the operator, as shown in Fig. 2, and the drill is so adjusted in its holder that its point rests upon the upper surface 66 of the anvil the drill is set to drill a hole three-eighths 120 of an inch deep in the heel 20.

125 In addition to the numerical indicia 38 upon the face of the gage 34 there is provided at 74 a letter S, designating one of the teeth 36 which is to be engaged by the hook 42 when the drill is to be adjusted in its holder. In the device illustrated herein the tooth S is two-eighths of an inch below the tooth 6 and therefore corresponds to a gage setting of 4-8. The length of the gage 34, from the 130

tooth S to the under surface 50 is such that when the hook 42 is engaged with the tooth S, the lower end of the gage inserted in the socket 60 with the shoulder 52 resting upon the surface 62, and the anvil 64 set at 3-8, the surface 50 of the lower end of the gage will be one-eighth of an inch below the horizontal line X-Y which defines the level of the upper face 66 of the anvil the drill and gage being maintained perpendicular to the surfaces 62 and 66 by the close fit of the gage in the socket 60. It will be apparent that if the drill 14 is now so adjusted in the chuck 12 that its point rests upon the anvil the point 15 of the drill will be one-eighth of an inch above the lower end 50 of the gage, and that if this setting of the gage and drill is preserved a hole three-eighths of an inch deep can be drilled in a 4-8 heel resting upon the 20 work support 22 before the feeding of the drill into the work is stopped by engagement of the gage with the surface of the work support.

If now it should be desired to drill a 3-8 25 hole in a heel of some other height, for example a 16-8 heel, it is only necessary to move the gage 34 until the hook 42 engages the tooth 16. The gage will then engage the surface of the work support and stop the feeding of the drill into the work when the drill has reached a point thirteen-eighths of an 30 inch above the work support and it will be easily seen that the required 3-8 hole has been drilled into the heel. Similarly for a 35 heel of any other height the gage is set by engaging the hook 42 with the correspondingly marked tooth 36 and the desired depth of hole in the work will always be produced regardless of the vertical position of the work 40 support and entirely independently of the height of the last 24.

If a hole of another depth is desired in the work the drill is adjusted in its holder as above described but with the anvil 64 set to 45 correspond to the depth of the hole which it is desired to drill.

In the ordinary use of the apparatus the drill will be set in the chuck to drill into the work to a depth of, say, one-half or five-eighths of an inch and left that way indefinitely, the only change in adjustment that is required thereafter being to reset the gage 34 when a change occurs in the height of the heels being operated upon.

Having described the invention, what is claimed as new and desired to be secured by Letters Patent is:

1. In a machine having a rotating drill holder, the combination of a gage carrier 60 having a clamp by which it may be secured to the machine in fixed longitudinal relation to the drill holder, a depth gage member movable through said carrier in a direction parallel to the axis of the drill holder, spaced 65 teeth upon the gage member, and a hook upon

the carrier arranged to engage any one of said teeth to secure the gage in various definite positions relatively to the drill holder.

2. In a machine having an upright drill holder, the combination, of a gage carrier secured to the machine in fixed longitudinal relation to the drill holder, a depth gage member movable through said carrier in a direction parallel to the axis of the drill holder, means for securing the gage member in various definite positions of adjustment in the carrier, and additional means for resisting movement of the gage member through the carrier sufficiently to prevent said member from dropping when the securing means is released.

3. In a machine having an upright drill holder, the combination of an upright gage holder, a gage member adjustable vertically in said holder, and a continuously effective, yielding, friction device operating automatically upon the gage member with sufficient force to prevent the weight of said member from causing it to move in its holder.

4. In a depth gage for drills, the combination of a carrier, a gage member slidabie in said carrier, and a continuously effective, yielding, friction device operating automatically to resist movement of the gage relatively to the carrier.

5. In a depth gage for drills, the combination of a carrier, a toothed gage member slideable in said carrier, a hook arranged to engage the teeth on the gage member, and a friction device operating continuously independently of said hook to resist movement of the gage member relatively to the carrier.

6. In a depth gage for drills, the combination of a carrier, a toothed gage member slideable in said carrier, a spring pressed hook arranged to engage the teeth on the gage member positively to lock said member against movement relatively to the carrier, and a friction cup continuously pressed against the gage member by the same spring which presses said hook.

In testimony whereof I have signed my name to this specification.

FREDERIC E. BERTRAND.
